DESIGN FOR A SHARPENING DEVICE

Hector J. Trinque, Gardner, Mass.

Application January 26, 1945, Serial No. 117,621

Term of patent 14 years

(Cl. D37—1)

To all whom it may concern:

Be it known that I, Hector J. Trinque, a citizen of the United States, residing at Gardner, in the county of Worcester and State of Massachusetts, have invented a new, original, and ornamental Design for a Sharpening Device, of which the following is a specification, reference being had to the accompanying drawing, forming part thereof.

Fig. 1 is a perspective view of a sharpening device showing my new design;

Fig. 2 is a side elevation thereof; and
Fig. 3 is a front view thereof.

I claim:

The ornamental design for a sharpening device, as shown.

HECTOR J. TRINQUE.
